UNITED STATES PATENT OFFICE.

BENJAMIN WRIGHT, OF HUDSON, MICHIGAN.

WASHING-MACHINE.

SPECIFICATION forming part of Letters Patent No. 237,653, dated February 8, 1881.

Application filed September 16, 1880. (Model.)

To all whom it may concern:

Be it known that I, BENJAMIN WRIGHT, of Hudson, in the county of Lenawee, and in the State of Michigan, have invented certain new and useful Improvements in Washing-Machines; and I do hereby declare that the following is a full, clear, and exact description thereof, reference being had to the accompanying drawings, and to the letters of reference 10 marked thereon, making a part of this specification.

My invention relates to that class of washing-machines in which a slatted segmental rocker oscillates over a segmental bed provided with cross-slats; and my improvements consist in making the curved bottom of my machine of thick zinc-plate and covering the same with alternately thick and thin removable slats, and divers improvements in the mode of construction, hereinafter particularly specified.

In the accompanying drawings, Figure 1 is a side elevation, in perspective, of my improved machine, with the rocker raised up to a vertical position upon its pivoted arms; and Fig. 2 is a vertical longitudinal section of the same with the rocker turned down to its working position.

A is the body of the machine, and B is a curved metal bottom, which I prefer to make of No. 18 zinc-plate. This metal plate is let into correspondingly-curved grooves in the side pieces of the machine, so as to make a water-tight joint. Said metal bottom is covered by a floor of alternately thick and thin cross-slats, b and b', and I prefer to make the thick slats with corrugated faces, as shown in Fig. 2. The ends of the thick slats are rabbed down to the same thickness with the thin slats, and all are held in place by segmental 30 cleats A' on each side of the machine.

At each end of the machine there is an inclined board, B', below the metal plate, with their ends inserted in grooves in the side pieces of the body, and across the center, under the 45 metal plate, is a wooden cross-bar, B'', secured to said side pieces. At the end opposite the hinged arms there is an inclined board, C, secured upon the inclined plate B' at that end of the machine, and its ends covering and closely 50 fitting down upon the segmental cleats A'. At the other end of the machine a beveled cross-strip, C', is similarly screwed down over the ends of said segmental cleats, and of about the same thickness as the thick slats b. These 55 strips C and C' hold the segmental cleats in

place; but the same may be further secured by a single screw, b'', at the central part of each. By unscrewing and removing the plate C all the slats b b' may be removed and replaced. At the end of the machine to which the hinged 60 arms are attached is another inclined cross-board, C'', secured to the side pieces of the body, and its upper surface being flush therewith.

D is a segmental rocker, having four or more 65 corrugated cross slats or dashers, d, and being journaled in two hinged or pivoted arms, D' D', and having a handle, h, at one end for oscillating the same. It will be seen that the center of the box is a little to one side of a 70 vertical central line through the axis of the segmental rocker. By having the center of the rocker-axis to one side of the center of the box there will be a greater space left between the rocker and the curved bottom of the box on 75 one side than on the other. The operator, being at that end of the box which has the greatest space, is enabled to feed in the clothing to be washed, and then the clothing is readily drawn down from this space into the box and 80 between the two washing-surfaces. The tendency of the rocker will be to steadily draw the clothing downward to be washed. This rocker, by means of said hinged arms, may be raised to a vertical position, as shown in Fig. 85 1. These arms are connected at their lower ends by a broad plate, e, and to the inner side of said plate is attached a beveled strip, e', which plate and strip serve to conduct any water dripping down from the rocker, when 90 raised to a vertical position, back into the body of the machine.

What I claim as my invention, and desire to secure by Letters Patent, is—

In a washing-machine, the curved metallic 95 bottom B, let into the sides of the body, in combination with the wooden floor b', composed of thin slats, with alternate thick but grooved slats b resting upon and supported by said bottom B, and with the segmental cleats A, which 100 confine the floor to the bottom, and the removable plate C, all arranged substantially as herein set forth.

In testimony that I claim the foregoing I have hereunto set my hand this 2d day of September, 1880.

BENJAMIN WRIGHT.
